UNITED STATES PATENT OFFICE.

ADDISON ARNOLD, OF CHARLOTTE, NORTH CAROLINA, ASSIGNOR TO J. W. CONWAY, OF CHARLOTTE, NORTH CAROLINA.

MEANS FOR TACKING ON CARD-CLOTHING.

No. 862,374.

Specification of Letters Patent.

Patented Aug. 6, 1907.

Application filed November 13, 1906. Serial No. 343,196.

To all whom it may concern:

Be it known that I, ADDISON ARNOLD, a citizen of the United States, residing at Charlotte, in the county of Mecklenburg and State of North Carolina, have invented a certain new and useful Means for Tacking on Card-Clothing, of which the following is a specification, reference being had therein to the accompanying drawing.

This invention relates to means for tacking on card clothing upon cylinders, doffers or any kind of reels using card clothing for carding cotton, wool, flax, hemp or any other carding, brushing or napping where fillet card clothing is used.

In carding machines, the cylinders require about two hundred and sixty eight feet of two inch clothing to cover the same; there are about three hundred wooden plugs to a cylinder and a tack must be driven through the clothing into each plug. As ordinary round flat headed tacks are used, approximately a quarter of an inch square of the teeth of the clothing is spoiled and rendered worse than useless for each tack. Furthermore holes or voids are thus formed in the teeth of the clothing which fill with the material, forming balls or wads which pass on to the doffer, etc. and impair the product of the machine.

The object of the present invention is to provide means whereby the objections above noted may be practically overcome, the card clothing being fastened to the cylinder or doffer without injuring or displacing any of the teeth, the clothing being left in perfect condition and producing much better results as a consequence thereof.

With the above and other objects in view, the nature of which will more fully appear as the description proceeds, the invention consists in the novel construction, combination and arrangement, herein fully described, illustrated and claimed.

In the accompanying drawings:—Figure 1 is a plan view of the device or machine of this invention, showing also a section of card clothing passing therethrough and secured by tacks of several kinds. Fig. 2 is a side elevation of the same illustrating the manner of using the apparatus. Fig. 3 is a longitudinal section through the same. Fig. 4 is a cross section thereof. Fig. 5 is a perspective view of one of the plows. Figs. 6 and 7 are detail views of two kinds of tacks employed in fastening the card clothing in place. Fig. 8 is a sectional elevation of the set used for driving the tacks.

Referring to the drawings 1 designates a section of card clothing having the usual teeth 2. This clothing may be of any width and, as is well understood, is put on the cylinder in strip form, the strip passing around

the outer surface of the cylinder and being fastened thereon.

In carrying out the present invention I employ a casing 3, which may be of sheet metal or any suitable material, and which embodies oppositely arranged parallel sides 4 and a connecting bottom 5 at right angles to the sides, as best shown in Fig. 4. Under the preferred embodiment of this invention the end portions of the sides 60 4 are low, that is to say they do not extend very high, while the middle portions of the sides are relatively high and form a housing for the guide, hereinafter described.

The guide 6 fits between the sides of the casing and 65 is fastened in place by one or more screws 7 or their equivalent. Said guide is in the form of a block which is provided in the bottom thereof with a series of parallel ways or grooves 8, in which a corresponding series of plows 9 are arranged to slide freely lengthwise of the card clothing. Each of said plows is constructed and shaped as shown in the detail view, Fig. 5, where it is seen to comprise the elongated body the bottom edge of which is brought to a fine edge, 70 as shown in Fig. 4 so as to wedge its way between the 75 rows of teeth of the clothing. The body of the plow is slotted longitudinally as shown at 10, and passing through all of the slots of the several plows is a stop 11, shown in the form of a round pin the ends of which are fast to the sides of the casing 3. This stop permits the plows to be moved lengthwise but arrests their movement in one direction and acts to line up the plows as the clothing passes through the casing onto the cylinder or doffer as the case may be, the clothing acting on the plows with sufficient friction 80 to drag them back to place in readiness for the tacking on operation, to be hereafter described. Each plow 9 is further provided with a tail portion 12 of a height not to extend much above the tops of the teeth of the clothing, and the extremity of said tail is split or 85 forked, while the arms or blades 13 of the fork are given an upward flare and divergence. The bottom edge of the tail part is also cut away as shown at 14 so that the space between the blades of the fork is left open at the bottom as well as the top, thus adapting the tacks, shown in Figs. 6 and 7 to be inserted between the blades of the fork at the top and pushed downward until they enter the body of the card clothing between the rows of teeth the tops of which have been spread apart by the plow.

The preferred form of tack is shown in Fig. 6 and designated 15, said tack embodying a long, narrow parallel-sided head the thickness or width of which is about one twenty-fourth of an inch, the distance

between adjacent rows of teeth on the clothing. Instead of the tack shown in Fig. 6, a double tack 16, of staple form, such as is shown in Fig. 7 may be used, the same width of head being retained so that the tack 5 head will lie between the bases of the teeth and not deflect or bend the same to the injury or impairment of the clothing.

In connection with the machine described, and the tacks referred to, I employ a tack set or driver 17, the 10 end of which is reduced until it is quite narrow and hollowed out or concaved as shown at 18 to fit over the tack head and prevent the set from slipping in the driving operation. At the other end the set is provided with a handle 19 in line with the longitudinal 15 axis of the recessed point 18 of the set, so that by holding the handle 19 directly in line with the length of the plows, the head of the tack is sustained in proper line while driving the same.

In operation, the machine is held over the cylinder 20 or doffer, and the latter turned until the split ends of the plows come over the wooden plugs of the cylinder. The cylinder is then stopped and the required 25 number of tacks are pressed between the blades of the forks into the plugs, through the card clothing. The set 17 is then applied to the heads of the tacks and driven down, the plows being slid out of the way, successively, by the operator's finger to permit the set and tack to be driven home.

The device may, of course be made of any width, 30 and any desired number of plows may be used according to requirements and the fineness of the card clothing as regards the number of teeth to the inch. Furthermore, the card clothing may be of any desired width and may be applied to a cylinder of any required size.

I claim:—

1. Means for tacking on card clothing comprising a guide, and a plurality of plows coöperating therewith and embodying means for indicating the positions or points at 40 which the tacks are to be driven.

2. Means for tacking on card clothing comprising a guide, and a plurality of plows coöperating therewith and

adapted to spread apart the teeth of the clothing, said plows having means for positioning the tacks prior to driving the same.

3. Means for tacking on card clothing comprising a guide, a plurality of plows working therein and adapted to spread apart the teeth of the clothing, and means on said plows for determining the positions of the tacks prior to driving the same.

4. Means for tacking on card clothing comprising a guide, and a plurality of plows working therein and having their ends split to receive and position the tacks between the rows of teeth of the clothing prior to driving the same.

5. Means for tacking on card clothing comprising a guide, a plurality of plows working therein and having means for determining the positions of the tacks prior to driving the same, and means for limiting the movement of the plows.

6. Means for tacking on card clothing comprising a guide, and a series of plows working therein in parallel planes and each embodying a teeth-spreading point and a split and forked end, substantially as described.

7. Means for tacking on card clothing comprising a guide, and a plurality of plows working therein and each embodying a teeth-spreading point and a split or forked part the blades or arms of which have an upward divergence.

8. Means for tacking on card clothing comprising a guide, a plurality of plows working therein and having means for positioning the tacks prior to driving the same, and a casting in which said parts are mounted.

9. Means for tacking on card clothing comprising a guide having parallel ways, plows working therein and adapted to slide lengthwise, and a stop common to all of the plows passing through a slot in each of the plows.

10. Means for tacking on card clothing comprising a guide having parallel ways, and plows working therein, each of the plows having a sharpened longitudinal edge, 80 a pointed teeth-spreading foot and means for determining the position of a tack prior to driving the same.

11. Means for tacking on card clothing comprising a guide having parallel ways, and plows working therein projecting beyond the guide adapting them to be moved lengthwise by hand and provided with means for determining the positions of the tacks prior to driving the same.

In testimony whereof I affix my signature in presence of two witnesses.

ADDISON ARNOLD.
